[57] ABSTRACT

In an electronic instrument having a storage unit, an automatic clearing device utilizes a portion of the storage unit as a constituent. A synchronizing signal generator generates a synchronizing signal in response to revolutions of an electric motor. A clear signal generating circuit generates output adapted to change from one state to another state when a power source is connected and to change from said another to said one state upon arrival of the synchronizing signal. A signal representative of the state change is applied to the storage unit portion as a clear signal, whereby the storage in the storage unit portion may be cleared.

6 Claims, 2 Drawing Figures

FIG. 1

FIG. 2

AUTOMATIC CLEARING DEVICE

BACKGROUND OF THE INVENTION

1. Field of the Invention

This invention relates to an automatic clearing device for electronic desk top calculators and other electronic instruments having a storage unit therein.

2. Description of the Prior Art

An electronic instrument such as electronic desk top calculator or the like has a storage unit such as a flip-flop, a shift register or the like. Since, however, such a storage unit is not reset to zero at the time when the power source for operating the electronic instrument is switched on, it has been necessary to depress a clear key to clear the content stored in the storage unit to zero after the power source has been connected.

To eliminate such a cumbersome procedure, a system known as the automatic clearing system has been put into use which can clear the storage unit upon connection of the power source. Such an automatic clearing system has mainly employed an arrangement wherein a time constant circuit capable of maintaining a signal at a predetermined level for a predetermined time after the connection of the power source is provided so that the output of such time constant circuit may be used to clear and control the storage unit.

Such an automatic clearing system, however, has required the time constant circuit to be of great capacity, it has formed a bottleneck in making the circuit more compact and also has led to a higher cost of manufacture.

SUMMARY OF THE INVENTION

It is an object of the present invention to present an automatic clearing device for electronic instruments having a storage unit which is of compact construction.

It is another object of the present invention to present an automatic clearing device for electronic instruments having a storage unit which does not need a capacitor of great capacity.

It is still another object of the present invention to present an automatic clearing device for use with electronic instruments having an electric motor.

Other objects, features and advantages of the present invention will become more apparent from the following detailed description taken in conjunction with the accompanying drawings.

BRIEF DESCRIPTION OF THE DRAWINGS

FIG. 1 is a circuit diagram showing the automatic clearing device according to the present invention; and

FIG. 2 shows signal waveforms in various parts of the clearing device of FIG. 1 for illustrating the operation of the device.

DESCRIPTION OF THE PREFERRED EMBODIMENTS

Referring to FIG. 1, there is diagrammatically shown a portion of an electronic desk top calculator which employs an electric motor for the purposes of generating a synchronizing signal, driving a printer and other purposes. A power supply unit 11 includes three different power sources 12, 13 and 14 which respectively supply voltages V_G , V_D , V_M and V_S through lines a , b ,

c and d to other circuit portions. In the respective lines there are provided power switches 15, 16, 17 and 18 which are associated with one another so that the power sources 12-14 may be simultaneously connected or disconnected to the lines $a-d$ by controlling the power switches.

An electric motor 19 has its drive terminals connected to the switches 17 and 18 and may be used to drive a printer (not shown) as well as to generate a synchronizing signal and for other purposes.

A disc 22 having magnets 21 mounted thereon is fixed on the rotary shaft 20 of the motor 19, and a pickup coil 23 is disposed in opposed relationship with respect to the magnet on the disc 22. Thus, energization of the motor 19 rotates the disc 22 and accordingly the magnet 21 adjacent to the pickup coil 23, so that a magnetic flux produced by the magnet 21 crosses the pickup coil 23, which will thus generate a pulse signal corresponding to the variation of the magnetic flux.

Such pulse signal is then amplified by an amplifier 24 to which power is supplied from power source 13 through lines b and d , thereby providing a pulse signal which forms a synchronizing signal supplied through line e to other circuit portions. In this case, some time delay exists from the time at which the power switches 15-18 are closed to supply the voltage V_M to the electric motor till the time at which the motor starts to revolve, and moreover, in the illustrated embodiment, there is also some time delay until the magnetic flux crossing the pickup coil reaches a predetermined velocity, i.e. from the time at which the power switches 17 and 18 are closed till a synchronizing signal is provided on the line e , because the amplifier 24 puts out only pulse signals of a predetermined level as the synchronizing signal.

A clear signal generator circuit, generally designated by 25, comprises a flip-flop circuit including MOS transistors 26-30, and a governor circuit for governing the initial state of the flip-flop circuit and including MOS transistors 31, 32 and a capacitor 33. The clear signal generator circuit 25 generates a clear signal through a line f . More specifically, the gate of MOS transistor 26 is connected to the line e to which the synchronizing signal from the amplifier 24 is applied, the source and drain of which are connected to the line d and on the one hand the gate of MOS transistor 27, respectively, and on the other hand to the drain of MOS transistor 30 and the source of MOS transistor 29, respectively. The source of MOS transistor 27 is connected to the line d while the drain of this transistor is connected on the one hand to the gate of MOS transistor 30 and on the other hand to the source of load MOS transistor 28. MOS transistors 28, 29 and 32 have their respective drains connected to the line b which is at the potential V_D and have their respective gates connected to the line a which is at the potential V_G , thus acting as a load. MOS transistor 31 has its drain and source connected to the source of MOS transistor 30 and the line d , respectively, and the gate of MOS transistor 31 has connected thereto the source of load MOS transistor 32 and one end of a capacitor 33, whose other end is connected to the line d which is at the potential V_S .

Numerical 34 generally designates a portion of the storage unit to be cleared, which includes flip-flop circuits 35 and 36 having set input terminals 37, 38, set output terminal 39, 40, reset input terminals 41, 42 and reset output terminals 43, 44, respectively. These

flip-flop circuits receive a clock pulse through a line *g*. The flip-flop circuits also have forced reset terminals 45 and 46 connected to the line *f* of the clear signal generator circuit 25, which line *f* has a terminal 47 for applying therethrough a clear signal to other storage unit portions (not shown).

In the automatic clearing device of the above-described construction, if the power switches 15-18 are closed at a point of time t_0 , the voltages such as V_g , V_D , V_M and V_S will be applied to the lines *a*, *b*, *c* and *d*, respectively. When voltages V_g and V_D are applied to the lines *a* and *b* as shown at A and B in FIG. 2, MOS transistor 32 acts as an impedance element of a predetermined impedance, through which the capacitor 33 is charged as shown at C in FIG. 2, with its terminal potential gradually approaching the potential V_D . In FIG. 2C, V_h represents the threshold potential of MOS transistor 31, which turns off when the gate potential of MOS transistor 31 is higher than the potential V_h and turns on when the gate potential of transistor 31 is lower than V_h .

Thus, MOS transistor 31 does not turn on until the point of time t_1 , i.e. until a period of time T_1 has elapsed from the initiation of the charging of the capacitor 33.

FIG. 2D shows the potential waveform appearing in the line *e* from the point of time t_0 at which the power switches have been closed as described until a synchronizing signal is provided. It is seen that the synchronizing signal cannot be provided simultaneously with the closing of the power switches at the point of time t_0 , but only after the lapse of a predetermined time T_2 , i.e. only at the point of time t_2 .

The capacitor 33 or the amplifier 24 is preset so that the periods of time T_1 and T_2 may be in the relation $T_1 < T_2$. As a result, MOS transistor 31 remains in OFF position during the period of time T_1 because the terminal potential of the capacitor has not yet reached its threshold as shown in FIG. 2C, and the transistor 26 also remains in OFF position because no synchronizing signal is yet applied to the gate thereof as shown in FIG. 2D, and thus the initial state of the flip-flop is governed by the transistor 31 and capacitor 33 and the potential across the line *f* presents the level V_D as shown in FIG. 2E. After such period of time has passed, the terminal voltage of the capacitor 33 reaches its threshold and the period of time T_3 is entered, whereupon MOS transistor 31 turns on. Still at this point of time, the transistor 26 remains in OFF position with no synchronizing signal yet applied thereto. As a result, the gate of the transistor 27 is turned on with the potential V_D applied thereto while the gate of the transistor 30 is turned off with the potential V_S applied thereto. Thus, the potential across the line *f* still remains at the aforesaid level V_D .

After such period of time has passed, a synchronizing signal is applied to the gate of the transistor 26 and the period of time T_3 is entered, whereupon the transistor 26 turns on with the arrival of the synchronizing signal while the transistor 27 is turned off but the transistor 30 is turned on. As a result, the potential across the line *f* is now at V_S as shown in FIG. 2E. It is due to the arrival of such pulse synchronizing that the gate potential of the transistor 27 reaches the level V_S as described, and therefore such state is continuously maintained whether the potential across the line *f* is thereafter varied to 0 or V_e .

Thus, such a clear signal as shown in FIG. 2E is produced from the line *f* and applied to the storage unit portion 34 to thereby clear the stored content therein.

I claim:

1. An automatic clearing device comprising: storage means whose storage is to be cleared upon connection of a power source to said device; synchronizing signal generating means for generating a synchronizing signal in accordance with revolutions of an electric motor driven by said power source;

clear signal generating means coupled to said synchronizing signal generating means for generating output, adapted to change from one state to another state upon connection of the power source and change from said another state to said one state upon arrival of said synchronizing signal; and

means coupled between said storage means and said signal generating means for applying as a clear signal to said storage means a signal resulting from the change of the state of said clear signal generating means.

2. An automatic clearing device according to claim

25 1, wherein said synchronizing signal generating means includes means for preventing said electric motor from generating a synchronizing signal until its revolutions attain a predetermined velocity after the power source has been connected.

3. An automatic clearing device comprising: storage means whose storage is to be cleared upon connection of a power source; synchronizing signal generating means for generating a synchronizing signal in accordance with revolutions of an electric motor;

35 clear signal generating means including a flip-flop circuit to which the output from said synchronizing signal generating means is applied as control signal, and means for determining the initial state of said flip-flop circuit, the output of said flip-flop changing from one state to another state determined by said means for determining upon connection of the power source and changing from said another state to said one state upon application of the synchronizing signal from said synchronizing signal generator means; and

40 means for applying as a clear signal to said storage means a signal resulting from the variation of the output of said clear signal generating circuit.

4. An automatic clearing device according to claim

50 3, wherein said means for determining comprises a capacitor and a switching element controlled by said capacitor.

5. An automatic clearing device according to claim 4, wherein said capacitor includes means for controlling said switching elements so that said switching element controlled by said capacitor is actuated after the connection of the power source in a shorter time than the time required from the connection of the power source until the synchronizing signal is generated.

55 6. An automatic clearing device according to claim 1, wherein said synchronizing signal generating means comprises a permanent magnet securely mounted on a rotary disc secured to the rotary shaft of said electric motor, a magnetic flux detecting element provided separately from said rotary disc and adjacent to said permanent magnet, and an amplifier for amplifying the signal detected by said detecting element.
